(57) **CLAIM**

The ornamental design for ceiling fan motor housing, as shown and described.

DESCRIPTION

FIG. 1 is a perspective view of the present design; FIG. 2 is a front view of the present design, the rear view of the present design being a mirror image thereof; FIG. 3 is a left side view of the present design, the right view of the present design being a mirror image thereof; FIG. 4 is a top view of the present design; FIG. 5 is bottom view of the present design; and, FIG. 6 is another perspective view of the present design. The broken lines in the drawings depict parts of the ceiling fan motor housing that form no part of the claimed design.
